UNITED STATES PATENT OFFICE.

GEORGE M. FARABOUGH, OF ROGERS, ARKANSAS, AND GROVER C. MOUTRAY, OF WICHITA, KANSAS; SAID FARABOUGH ASSIGNEE OF HIS ENTIRE RIGHT TO JESSIE A. FARABOUGH, OF ROGERS, ARKANSAS.

VAULT LOCK.

Application filed January 28, 1924, Serial No. 689,152.

To all whom it may concern:

Be it known that we, GEORGE M. FARABOUGH and GROVER C. MOUTRAY, citizens of the United States, residing at Rogers, county 5 of Benton, and State of Arkansas, and Wichita, in the county of Sedgwick and State of Kansas, respectively, have invented certain new and useful Improvements in Vault Locks, of which the following is a 10 specification.

The present invention relates to a vault lock and more particularly to a device which I designate as a daylight protector to be installed on a vault door of a bank or like 15 institution.

The principal object of the invention is to prevent bank robbers and the like from locking the bank employees in the vault. The installation of this protector allows the 20 door to be closed with the exception of about one inch. When in this position it automatically locks so as to remain in this position and the door cannot be further closed nor can it be opened from the outside without the use of a specially built tool. This 25 arrangement allows the occupants of the vault to be in perfect safety during robbery and also allows them to have sufficient air. The door of the vault may readily be unlocked from the inside.

Another important object of the invention is to provide a device of this nature possessed of a simple and efficient construction, one 30 which is reliable, comparatively inexpensive to manufacture and install, durable, and well adapted to the purpose for which it is designed.

With the above and numerous other objects in view, the invention resides in certain novel features of construction and in the combination and arrangement of parts as 40 will be hereinafter more fully described and claimed.

In the drawings:

Figure 1 is a fragmentary horizontal section taken through a vault and the door thereof showing my locking device associated therewith for holding the door in a 45 partially closed position,

Figure 2 is a section taken through the vault vertically substantially on the line 2-2 of Figure 1,

Figure 3 is a perspective view of the lock, and

Figure 4 is a fragmentary elevation there- 55 of showing particularly the latch.

Referring to the drawing in detail it will be seen that 1 designates the vault which is provided with the usual door 2. The portions of the vault and the door which abut each other are usually provided with a stepped construction as indicated at 3. The parts thus far designated are of a conventional construction and they are merely illustrated by way of example so as to more 60 clearly explain the operation and utility of the lock about to be described.

The preferred embodiment of the lock consists of a supporting bar 4 fixed to the inner wall of the vault by a plurality of 70 bolts 5 or in any other suitable manner. This supporting bar 4 is provided at its end adjacent the door 2 with an offset extension 6 spaced from the inner surface of the vault wall. An extension bar 7 forming the body of the lock is attached to the offset extension 6 by means of bolts 8 or in any other suitable manner. This body extension 7 and the supporting bar 4 are 75 disposed horizontally and the body extension 7 is positioned adjacent the door 2. A latch bar 9 is pivoted adjacent one end to a bolt 10 which is supported by the body extension 7 adjacent one end. The outer 80 end 11 of the latch bar is curved and a notch 12 is disposed or formed on the under edge thereof adjacent the curved end 11. As is disclosed to advantage in Figure 1 the latch bar 9 is pivoted on the inner face 85 of the body extension 7. On the outer face of this body extension 7 there is positioned a spring member 13 disposed vertically and held in place by bolts or screws 14 and 15. The bolt 14 pierces the body extension 7 90 and extends beyond the inner face thereof so that the latch bar 9 may rest thereon in a substantially horizontal position as is indicated to advantage in Figure 4. A rod 16 pierces the body extension 7 intermediate 95 its ends and is provided with an inner head 17 and an outer head 18. A spring 19 of the compressible helical type is positioned about the rod 16 between the outer surface of the body extension 7 and head 18 so as to normally hold the inner head 17 against the inner face of the body extension 7. As 100 is disclosed to advantage the inner end of the head 17 and rod 16 is so disposed as

90

95

100

105

to abut the inner end of the latch bar 9 so that when the latch bar is in a substantial horizontal position it is impossible to swing the same. Furthermore, if the rod 16 is 5 pushed inwardly this latch bar may be readily swung to an angular position in relation to the body extension and will be held in this position when the head 17 returns into abutment with the body extension. If the 10 latch bar 9 is swung to a vertical position the lip extension 20 of the spring member 13 will frictionally engage one face thereof and hold the latch bar in this position.

A keeper 21, substantially L-shaped in 15 formation has one of its legs fixed to the door 2 and the other leg is engageable by the latch bar 9. When the vault is opened, the latch bar should be disposed in a substantial horizontal position. If, now, the 20 door 2 is closed the bolt 9 will engage the keeper so that one leg of the latter will be disposed in the notch 12 thus holding the door ajar. It will be readily understood and seen that this door cannot be opened 25 or closed from the outside when in this position and with the space provided by the door being ajar will allow plenty of ventilation for any occupants of the vault. The occupants of the vault may readily release the 30 lock by pushing inwardly on the rod 16 and lifting the latch bar out of engagement with the keeper.

The construction and operation of this 35 invention should now be clearly understood without a more detail description thereof. It is, however, desired to point that numerous changes in the details of construction, and in the combination and arrangement of parts 40 may be resorted to without departing from the spirit or scope of the invention as hereinafter claimed or sacrificing any of its advantages.

Having thus described our invention 45 what we claim as new is:

1. A device of the class described including in combination a support, a latch bar pivoted adjacent one end to the support, a push rod piercing the support and slid-

able transversely therethrough, a head on 50 the rod disposed when in abutment with the support so as to prevent swinging of the latch bar, and yieldable means normally holding said head in abutment with the support. 55

2. A device of the class described including in combination a body, a latch bar pivoted to the body, a pin projecting from the body for supporting the latch bar in substantial alinement with the body, a rod 60 piercing the body and movable therethrough, a head on the rod adapted to abut the body adjacent one end of the latch bar when alined with the body so as to prevent swinging thereof, and a spring associated with the rod to normally hold the head in abutment with the body. 65

3. A device of the class described including in combination, a body, a keeper, a latch bar cooperating with the keeper and pivoted on the body, positive manually releasable means for holding the latch bar in an upwardly swung released position or a horizontal latching position, and means arranged to frictionally engage the latch bar 70 to hold it in a released upwardly swung vertical position. 75

4. In combination, a vault having a door, a latch in the vault, a keeper on the door 80 adapted to be engaged by the latch when the door is nearly closed to hold the latter in a partly open position, and means for releasably holding the latch in latching and released positions, said last named means being located within the vault a distance from the door so as to be non-releasable from a point exteriorly of the vault when the door 85 is held in such partly open position by engagement of the latch with the keeper. 90

In testimony whereof we affix our signatures in presence of two witnesses.

GEORGE M. FARABOUGH.
GROVER C. MOUTRAY.
